(57) **CLAIM**

The ornamental design for a display screen or portion thereof with graphical user interface, as shown and described.

DESCRIPTION

2. Display screen or portion thereof with graphical user interface

3. Display screen or portion thereof with graphical user interface

4. Display screen or portion thereof with graphical user interface

2.1: Front

3.1: Front

4.1: Front

FIGS. 2.1, 3.1, and 4.1 show three embodiments of a display screen or portion thereof with graphical user interface. The broken line showing of a display screen or a portion thereof is for the purpose of illustrating environment and forms no part of the claimed design; the broken line showing of graphical user interface elements on the display screen illustrates portions of the graphical user interface and form no part of the claimed design.
